CARTRIDGE FEEDING MAGAZINE FOR
FIREARMS

Alton M. Olson, Seattle, Wash.

Application February 27, 1948, Serial No. 11,432

4 Claims. (Cl. 42—17)

1

This invention relates to improvements in firearms, and more particularly to a magazine rifle which is cleared and loaded by movement of the breech mechanism.

It is among the objects of the invention to provide an improved magazine rifle which will receive an entire box of cartridges at one loading of the magazine and may receive the cartridges in the same arrangement in which they are packed in the box so that the contents of a cartridge box may be inserted as a unit into the magazine of the rifle instead of separately inserting the cartridges, as is necessary with conventional magazine rifles, in which the cartridges are automatically turned from a position transverse to the rifle barrel to a longitudinal position before insertion into the barrel chamber and are presented to the chamber with the cap and bullet ends properly disposed regardless of the relative transverse position of the ends, which is operative to divide the total number of cartridges conventionally contained in a cartridge box into several units, each including a predetermined number of cartridges so that a string of a predetermined number of shots can be gotten off without having to count the shots, and which provides a simplified mechanism including a minimum number of simple parts which cooperate without jamming or binding, are easy to assemble and disassemble, and economical to manufacture, and in which the operative mechanism is completely enclosed to protect it from dirt and moisture and provide a neat and attractive appearance for the rifle.

Other objects and advantages will become apparent from a consideration of the following description in conjunction with the accompanying drawings, wherein:

Figure 1 is a side elevation of a fragmentary intermediate portion of a magazine rifle illustrative of the invention;

Figure 2 is a longitudinal cross-section of the fragmentary rifle portion illustrated in Figure 1;

Figure 3 is a top plan view of the fragmentary rifle portion illustrated in Figure 1;

Figure 4 is a transverse cross-section taken substantially on line 4—4 of Figure 3;

Figure 5 is a bottom plan view of the breech bolt of the rifle mechanism shown in Figures 1 to 4 inclusive;

Figure 6 is a longitudinal elevation similar to Figure 1, but with parts broken away showing cartridges in the rifle magazine and a part of the cartridge feeding mechanism of the magazine;

Figure 7 is an elevation similar to Figure 6

2

showing other parts of the cartridge feeding mechanism;

Figure 8 is a top plan view of a fragmentary portion of the magazine rifle illustrated in the above-described figures showing the breech bolt open and a cartridge passing from the magazine to the breech of the mechanism;

Figure 9 is a view similar to Figure 8 showing a cartridge in position to enter the cartridge chamber in the barrel of the rifle;

Figure 10 is a longitudinal elevation similar to Figure 1 showing a modified form of magazine mechanism, a portion being broken away to more clearly illustrate the construction thereof;

Figure 11 is a longitudinal elevation of the modified form of magazine rifle shown in Figure 10 with the cartridge receiver of the magazine projected for insertion of the contents of a box of cartridges therein;

Figure 12 is a transverse cross-section substantially on line 12—12 of Figure 10;

Figure 13 is a longitudinal cross-section of a fragmentary portion of a magazine rifle showing a further modified form of cartridge feeding mechanism;

Figure 14 is a side elevation of the further modified form of cartridge feeding mechanism illustrated in Figure 13;

Figure 15 is a longitudinal cross-section of a fragmentary intermediate portion of a magazine rifle showing a still further modified form of magazine mechanism;

Figure 16 is a top plan view of the modified magazine mechanism shown in Figure 15;

Figure 17 is a transverse cross-section taken substantially on line 17—17 of Figure 15;

Figure 18 is a longitudinal cross-section of a fragmentary intermediate portion of a magazine rifle showing another modified form of magazine mechanism;

Figure 19 is a top plan view of the modified construction shown in Figure 18;

Figure 20 is a side elevation of the magazine shown in cross-section in Figure 18; and

Figure 21 is a bottom plan view of the magazine shown in side elevation in Figure 20.

With continued reference to the drawings, and particularly to Figures 1 to 9 inclusive, the rifle therein illustrated generally comprises a barrel 10, a hollow forearm 11, a receiver 12, a breech bolt 13, and a stock 14.

Barrel 10 is of conventional construction and is provided with a cartridge chamber 15 at the rear end of the bore 16. The barrel is rigidly secured at its rear end to the top plate 17 of the

receiver 12, which receiver has a bottom plate 18 spaced from the top plate 17 and rigidly secured thereto and provided with a downwardly-projecting apertured boss 19 which receives the screw-threaded inner end of a screw 20 which connects the stock 14 to the receiver, the forward end of the stock being guided between the downwardly-projecting side plates 21 of the hollow receiver so that the stock is rigidly secured to the receiver by the releasable connection including the screw 20 and is held rigidly in alignment with the barrel 13.

Top plate 17 of the receiver is provided with a longitudinal trackway which slidably receives a longitudinal guide 23 provided on the lower surface of the breech bolt 13.

The breech bolt comprises a tubular body 24, one end portion of which is fixed in a tubular sleeve 25 to which the guideway 23 is secured and the other end portion of which is surrounded by a loose sleeve 26 rotatable and slidably thereon. A bolt lever 27 extends radially outwardly from the loose sleeve 26 and is provided at one side adjacent sleeve 26 with an abutment 28 engageable with a shoulder 29 formed on the corresponding side plate 21 of the receiver to lock the breech bolt in the closed position, illustrated in Figures 1 and 2, for firing the rifle.

At its forward end the tubular body 24 is provided with a tauck end wall 30 apertured to receive the firing pin 31, which pin has an abutment portion fitting the interior of the tubular body 24 at the inner side of end wall 30. A hammer 32 is slidably mounted in the tubular body 24 at the forward end of the forward reduced portion 33 of a rod 34 which extends through the hollow body 24 of the breech bolt and is slidable therein. At its rear end the rod 34 is provided with a knob 35 for cocking and locking the hammer in cocked position and is surrounded intermediate its length by a coiled compression spring 36 which is operative to drive the hammer 32 against the inner end of firing pin 31.

Tubular body member 24 is provided with an elongated slot 28' in its rearward under surface through which a trigger-operated sear 38 extends to engage at its upper end a shoulder 37 provided at the forward end of the larger rearward portion of rod 34 from which the reduced portion 33 extends. Sear 38 extends upwardly from the stock through aligned apertures in the top and bottom walls of the receiver and is pivotally connected at its lower end to a trigger 39 pivotally mounted on the stock 14 and protected by a trigger guard 40.

With this arrangement, when the breech bolt 13 is drawn backwardly to its rearward position the trigger-operated sear 38 engages shoulder 37 and retains the rod 34 in its rearward position while the breech bolt is moved forwardly thereby compressing the firing spring 36. When the trigger is pulled the sear is withdrawn from the shoulder releasing the rod and the spring drives the hammer 32 against the rear end of the firing pin 31 to discharge a cartridge in the barrel chamber 15.

It will be noted that in the above-described receiver and breech bolt mechanism the breech bolt does not rotate in the receiver, but instead, the sleeve 26 carrying bolt lever 27 rotates upon the breech bolt so that the lever can be cleared from the shoulder 29 for rearward movement of the bolt. The bolt has only a longitudinal movement forwardly and rearwardly of the receiver and is guided in this movement by the trackway 75

on the receiver and the guideway 23 on the bottom surface of the bolt.

The stock 14 is of conventional design and construction and a detailed description thereof is not considered necessary for the purposes of the present disclosure.

The forearm 11 is a hollow casing of generally rectangular, cross-sectional shape having the forward portion of its bottom wall forwardly and upwardly inclined to a front wall 41 which is welded or otherwise suitably secured to the barrel 10. The rear wall 42 of the forearm abuts the front end surface of the stock 14 and is secured to the receiver 12 so that the forearm is held rigidly in place relative to the receiver, the stock and the barrel and serves to reinforce the connection between the barrel and the stock.

The right-hand side wall 43 of the forearm is cut away at its rearward end to provide a rectangular recess of substantially the same size and shape as a conventional cartridge box and this recess is covered by a slideable cover plate 44 which is disposed against the inner side of the side wall 43 and is provided with a finger knob 45 by means of which the cover plate can be slid forwardly to uncover the recess and rearwardly to re-cover the recess, when desired. When the cover plate is slid forwardly to uncover the recess the finger knob 45 is received in a recess 46 provided in the rear end portion of the forearm side wall 43.

A cartridge elevator in the form of an elongated, flat plate 47 having longitudinally-extending lateral flanges is positioned in the rearward portion of the forearm and extends longitudinally of the recess provided by the cut-away rear end portion of the side plate 43. This elevator is positioned against the bottom wall 48 of the recess portion of the forearm or magazine when the magazine cover plate 44 is moved forwardly and is resiliently urged upwardly to force cartridges in the magazine against the movable top wall 49 of the magazine when the cover plate is moved rearwardly to cover the side opening of the magazine.

The movable top wall 49 of the magazine is movable forwardly and rearwardly by a mechanism, presently to be described, and is spaced below the fixed top wall 88 of the magazine a distance substantially equal to the major diameter of a cartridge which the rifle is designed to fire.

The rearward end of the elevator plate is pivotally connected at its under-surface to the rearward end of an elongated lever 50 which extends forwardly through the portion of the forearm interior ahead of the magazine and has its forward end portion bifurcated and extended upwardly to provide a pair of apertured lugs 51 pivotally mounted on a transverse pin 52 extending through the forearm and supported in apertures provided in the forearm side walls. The forward end of the elevator plate 47 is pivotally connected at its under-side to the rearward end of a lever 53, the forward end of which is bifurcated and pivotally supported on a pin 54 which extends transversely of the forearm adjacent the bottom wall thereof and near the forward end of the magazine and is supported in elongated slots 55 provided in the lower edge portions of the forearm side walls.

The elevator plate 47 is resiliently urged toward the movable top plate 49 of the magazine by a torsion spring 56 carried by the lever 53 intermediate its length and acting against the

plate 47 near the pivotal connection between the plate and the lever 53.

A guide bar 57 is secured at its rearward end to the cover plate 44 and extends forwardly inside of the forearm 11 adjacent the inner side of the right-hand side-wall 43. In the illustrated arrangement this guide bar is formed of two thin members of similar shape spaced apart and rigidly secured together in over-lapping relationship. A lever 58, particularly illustrated in Figure 7, lies between the two sides of the guide bar 57 and has its rearward end pivotally connected to the guide bar by a suitable pivot pin 59. This lever has in its lower side a notch 60 which cooperates with a pin 61 extending transversely through the guide bar to limit downward movement of the forward end of the lever. The forward end of the lever is urged downwardly by a coiled compression spring 62 interposed between the rearward end of the lever and an apertured abutment 63 projecting upwardly from the guide bar 57 which spring surrounds a guide pin 64 pivotally connected at its forward end to lever 58 and passing slidably through the aperture in abutment 63. The forward end of lever 58 is provided with a notch 65 which is opposed to a transverse pin 66 extending through a loop 67 provided at the forward end of an elongated leg 68 of the lever 53 when the elevator plate 47 is in its raised or upper position, as illustrated in Figure 2.

Lever 50 passes between the sides of the bifurcated upper or rearward end portion of lever 53 and rests upon a transverse bead 69 provided on lever 53, being held against this bead, by the action of spring 56. Thus, lever 50 is guided upon lever 53 in a manner to maintain elevator plate 47 parallel to the top plate 49 of the magazine as the elevator plate moves up and down in the magazine.

With the construction so far described, when the cover plate 44 is moved forwardly to uncover the side of the magazine, the lever 58 engages with its notched end the pin 66 carried by the forwardly-extended leg of lever 53. Lever 53 is generally in the form of a bell-crank lever and is pivoted at the bend intermediate its length on pin 54, which is slidably supported in side-wall slots 55. As forward movement of the cover plate 44 is continued, the forward end of lever 58 rises raising the forward end of lever 53 and turning lever 53 about its pivotal connection with pin 54. This forces the rearward end of lever 53 downwardly carrying with it the forward end of elevator plate 47. As lever 50 is supported on the bead 69 of lever 53 and held against this bead by torsion spring 56 the rearward end of lever 50 is also carried downwardly, the front end of this lever pivoting about transverse pivot pin 52. As the rearward end of lever 53 moves downwardly, pin 54 moves forwardly in slots 55 so that the rearward end of this lever moves in a substantially vertical rather than in an arcuate path as would be the case if pin 54 were fixed. The rearward ends of levers 53 and 50 move together at substantially the same rate so that plate 47 is maintained substantially parallel to plate 49 at all positions as the elevator plate 47 is moved from the top to the bottom of the magazine chamber.

A slide 70 extends across the inner-surface of the bottom wall of forearm 11 immediately in front of the magazine chamber and has lateral flanges provided with elongated slots 71 through which the pin 54 extends so that the slide is

movable forwardly and rearwardly of the forearm to a limited extent. At its rearward end slide 70 is provided with a pair of upstanding abutments 72 disposed one at each side of the forward end of the magazine chamber, which abutments constitute a movable front end for the chamber. Rearward movement of the slide 70 is limited by a shoulder 73 formed in the bottom wall of the forearm 11 at the front end of the magazine chamber and the slide is resiliently urged to its rearward position against this stop, by a coiled compression spring 74 which is interposed between the front end of the slide and the pivot pin 52 and surrounds a guide pin 75 which is rigidly secured at its rearward end to the slide 70, as by being welded or soldered thereto, and has its forward end bifurcated to slidably receive the transverse pivot pin 52. Slide 70 is provided with a laterally-extending hook 76 which passes around the lower edge portion of guide bar 57 and lever 58 is provided at its rearward end with an extension 77 which projects downwardly below the guide bar 57 when lever 58 is in the upright position, illustrated in Figure 7, and engages the hook 76 of the slide just before the cover plate 44 reaches its forward limiting position to move the slide 70 forwardly a slight amount when the cover plate is moved to its limiting forward position to thereby slightly increase the length of the magazine chamber to facilitate insertion of the contents of a box of cartridges therein.

When the cover plate is returned to its rearward position covering the open side of the magazine chamber, the slide 70 is moved rearwardly by the spring 74 against the stop shoulder 73 so that the abutment 72 presses against the forward side of the block of cartridges in the magazine chamber and properly positions the cartridges in the chamber.

After the cartridges have been positioned in the chamber and the cover plate 44 closed, the block of cartridges in the magazine chamber is resiliently urged rearwardly by the slide abutments 72 and is resiliently urged upwardly by the elevator plate 47 upon which it rests.

The top wall 17 of the receiver is extended forwardly to provide a fixed top wall 80 for the magazine chamber, this combined top wall being transversely slotted at 81 to permit the passage of a single cartridge through the feed slot from the magazine to the top of the top wall 17 of the receiver. A pair of spaced-apart, inclined ramps 82 are provided at the rear end of the magazine extending upwardly and rearwardly to the rear edge of slot 81 to guide the cartridges through the feed slot, these ramps being adjacent to, but preferably spaced somewhat inwardly of the corresponding side walls of the magazine.

The movable top wall 49 of the magazine chamber is secured at its front end to a foot 83 provided at the rearward end of a plunger 84 which extends forwardly through the hollow forearm 11 and is guided intermediate its length in an apertured lug 85 which projects forwardly from a transverse support 86 extending across the interior of the forearm and secured to the side walls thereof, and in an aperture provided in the front wall 41 of the forearm.

This plunger 84 is movable forwardly and rearwardly of the forearm and is resiliently urged in a forward direction by a coiled compression spring 87 which surrounds the plunger between the forward end of the lug 85 and an abutment

washer 88 secured on the plunger. At its forward end the plunger is provided with a manually-depressible latch 89 engageable with an edge of the aperture in the front wall 41 and with a knob 88.

An upstanding apertured lug 81 is secured to the plunger 84 between the lug 88 and the plunger foot 83 and slidably receives the forward-end portion of a cartridge pusher 82. A coiled compression spring 83 surrounds the cartridge pusher between the lug 81 and an abutment washer 84 fixed on the pusher to resiliently urge the pusher rearwardly relative to the lug 81, rearward movement of the pusher relative to the lug being limited by a nut 85 secured on the forward end of the pusher.

With the above-described mechanism, assuming that there are cartridges upon the elevator plate 47 in the magazine chamber, and none in the space between the movable top wall 48 and the fixed top wall 88 of the magazine, the detent 88 is manually released and the spring 87 forces the plunger 84 forwardly until the rear end of cartridge pusher 82 is brought to a position just forward of the front end of elevator plate 47. In this position of the pusher and with the movable top wall 48 of the magazine also moved forwardly out of the way, the elevator plate will lift the cartridges carried thereon until a row of cartridges is raised against the undersurface of the fixed wall 88 of the magazine. These cartridges are disposed transversely of the fixed top plate of the magazine and may be in alternatively-opposite, end-to-end relationship just as they come from the cartridge box. The plunger 84 is then forced inwardly by manual pressure on the knob 88 until the detent 81 latches the front wall 41 of the forearm. This inward movement of the plunger forces the movable top wall 48 between the top row of cartridges and the next succeeding row, thereby separating the top row and holding it between the fixed wall 88 and movable wall 48 at the top of the magazine. The rearward end of the pusher 82 bears against the front cartridge of the top row and the spring 83 is compressed allowing the pusher to slide forwardly relative to the lug 81. A row of transversely arranged cartridges is then held between the magazine walls 88 and 48 and resiliently urged rearwardly by the force of compression spring 83 so that the rearward cartridge of the row is forced up the ramps 82 and presented at the cartridge feeding slot 81 in the top wall of the receiver.

Cartridges are usually packed fifty in a box, and the magazine may be dimensioned to receive a block of fifty cartridges representing the entire contents of a conventional cartridge box. These cartridges may be arranged in the magazine in five vertically-spaced, horizontal rows of ten cartridges each so that forward and rearward movement of the plunger 84 conditions the rifle for firing ten shots before another movement of the plunger is necessary. Thus, the entire cartridge contents of a box may be divided into strings of ten shots and it is not necessary for the rifleman to count the shots in each string. Obviously, any other desired number of cartridges may be inserted as the original cartridge block, and this block may be sub-divided as may be found desirable.

The arrangement of cartridges in the magazine chamber and the forward position of the plunger 84 is particularly illustrated in Figure 6.

The cartridge pusher 82 is also shown in this figure as positioned at the forward end of the top row of cartridges 88, so that when the plunger 84 is forced rearwardly and spring 83 compressed, the pusher will resiliently urge the top row of cartridges rearwardly against the ramps 82.

With the magazine conditioned, as above-described, for loading of the gun, and assuming the breech bolt 13 to be locked in its forward position, as illustrated in Figure 1, in order to load or reload the rifle, the breech bolt lever 21 is first raised to a position as illustrated in Figure 6, at which it clears the bolt locking shoulder 29 and the breech bolt is then slid rearwardly to its limiting rear position. As the breech bolt moves rearwardly the bottom edges of the trackway 23 ride upon the top surface of the cartridge presented at the feed slot 81 in the magazine until the forward ends 87 of the trackway edges pass to the rear of the cartridge permitting the cartridge to rise upwardly through the feed slot into the breech mechanism. When the bolt 13 is now moved forwardly, the trackway ends 87 serve as prongs which engage the rearward side of the cartridge and force it forwardly in the receiver toward the rear end of the barrel.

The receiver has a pair of spaced-apart, substantially parallel vertical walls 88 which extend rearwardly from the rear end of the barrel for a portion of the length of the receiver. Each of these walls is provided in its lower portion adjacent the receiver top wall 11 with a longitudinal extension 89 of substantially semi-circular cross-sectional shape which extensions are concavely opposed to each other at opposite sides of the receiver and are spaced apart a distance substantially equal to the length of a cartridge. These extensions receive the cartridge rising through the feed slot 81 and prevent it from rising out of the receiver of the rifle. They also constitute a guideway for the cartridge as it is forced forwardly of the breech mechanism by forward movement of the breech bolt 13. At their upper edges the side-walls 88 are provided with concavely-opposed beads 100 which constitute grooves receiving laterally-projecting flanges 101 on the front end of the breech bolt to assist in guiding the breech bolt in a straight path forwardly and rearwardly of the receiver.

The semi-circular extensions 89 are curved inwardly at their forward ends, as indicated at 102, and converge to a ramp 103 which is disposed at the rear end of the barrel immediately below the chamber 16 and which is inclined forwardly and upwardly from the top wall of the breech to the barrel chamber. The cross-sectional curvature of the forward, converging portions of extensions 89 is such that the bullet end of the cartridge will pass through the concave interiors of the extensions, but the cap end will not pass through and will, therefore, be retarded in the movement of the cartridge toward the barrel chamber. This serves to turn the cartridge so that the bullet end thereof is first presented to the barrel chamber regardless of the relative end-to-end position of the cartridge transversely of the breech mechanism when fed through the feed slot 81.

A small, U-shaped member 104 is slidably secured to the breech bolt under the forward end thereof by a longitudinally-extending strip 105 which extends along the forward portion of the trackway between the two sides thereof. This 75 U-shaped injector member has its sides extend-

ing forwardly of the breech bolt and disposed one at each side of the guideway 23, as is clearly shown in Figure 5. A pin 106 is secured to the rearward closed end of the U-shaped injector 104 and is slidably guided in a portion 107 of the guideway having a pin-enclosing bottom wall. A coiled compression spring 108 surrounds the pin between an abutment provided at the rearward end of the guideway portion 107 and an abutment washer 109 secured on the rearward end of the pin to resiliently urge the injector 104 to its rearward position relative to the breech bolt in which its closed end is in contact with the forward end of the guideway portion 107. The injector 104 has on its upper surface a projection 110, Figure 2, which is engaged by the forward end of sleeve 26 as the breech bolt lever is moved forwardly. When the sear 38 engages shoulder 37, the breech bolt will be momentarily stopped since spring 36 is stronger than spring 108, and during this time sleeve 26 to which bolt lever 27 is secured, will move forwardly of the breech bolt carrying with it the injector 104 and the front end face of one of the injector legs will come into contact with the cap end of the cartridge in the guide extensions 102 and force the cartridge up the ramp 103 and into the chamber of the barrel. The extent of sliding movement of the sleeve 26 on the breech bolt is only sufficient to move the injector from its retracted position, illustrated in Figure 5, to a position in which the front ends of its legs are flush with or slightly beyond the front ends 97 of the forward guideway sides. As soon as the injector has been brought to this position, the front end of sleeve 26 contacts the rear annular shoulder of the front wall 30 of the breech bolt and forces the entire bolt forwardly compressing spring 36 to move hammer 32 away from firing pin 31 and cock the firing mechanism of the rifle. When the front end of the breech bolt has been brought against the rear end of the barrel the lever 27 may be turned downwardly to engage the shoulder 29 and lock the breech bolt in its forward position with the firing spring 36 compressed. The forward end portion of sleeve 26 is provided with a longitudinal slot 111 and, when the lever 27 is turned down, sleeve 26 is rotated until this slot is brought into alignment with the extension 110 on the injector which permits spring 108 to retract the injector to its rearward position, illustrated in Figure 5, in which position it is operative to inject the succeeding cartridge into the chamber.

A cartridge extractor 112 is carried by the front end of the breech bolt in position such that it enters the upper rear portion of the chamber 15, as is clearly illustrated in Figure 2, and engages the rim on the cap end of the cartridge.

The improved mechanism illustrated in Figures 1 to 9 inclusive, thus provides a cartridge magazine in which a block of cartridges representing the entire contents of a conventional cartridge box can be inserted at one time, and in a manner such that the cartridges will be disposed transversely of the barrel of the rifle, which is operative to divide the block of cartridges into groups, each containing a number of cartridges less than the total number contained in the box, which is operative to feed these cartridges one at a time to the receiver of the rifle, to inject the cartridges into the cartridge chamber in the rifle barrel regardless of the relative end-to-end position of the cartridge in the receiver, and to effectively eject the empty jacket from the barrel after the cartridge has been fired.

The form of the invention shown in Figures 13 and 14 is substantially the same in all details as that shown in Figures 1 to 9 inclusive, and illustrated above, except that the arrangement of the levers supporting the cartridge elevator plate 47 is somewhat different. In this arrangement the forward end of plate 47 is pivotally connected at its under-side to the rear end of an elongated lever 113 which extends forwardly through the hollow forearm 11 and is pivotally connected to the forearm at its front end by a pivot pin 114 which extends transversely through the forearm and is secured at its ends in the side walls thereof. The rearward end of the plate 47 is pivotally connected at its under-side to the rear end of an elongated lever 115 which also extends forwardly through the hollow forearm and is pivotally mounted intermediate its length on a transverse pivot pin 116 which extends transversely through the hollow forearm rearwardly of the pin 114 and is secured at its ends in the side walls of the forearm. A coiled compression spring 117 is interposed between the levers 113 and 115 and between the pivot pins 114 and 116 so that one end of the spring bears downwardly on the end portion of lever 115 ahead of the corresponding pin 116 tending to raise the rearward end of this lever, and the upper end of the spring bears upwardly on a portion of lever 113 to the rear of pivot pin 114 tending to simultaneously raise the rearward end of this lever. Thus, the plate 47 is resiliently urged upwardly by the force of spring 117 and is held substantially parallel to the top and bottom walls of the magazine chamber 118 by the geometry of the levers. A bell crank lever 119 is pivotally mounted adjacent its intermediate bend on the pin 116 and is provided at its forward end with a loop 120 corresponding to the loop 67 on lever 53 and supports a pin 121 corresponding to pin 66. Pin 66 is engageable by the notched forward end of lever or link 58 carried by guide bar 57 of the magazine cover plate 44 in the same manner as explained above in connection with Figures 2 and 7, so that the forward end of lever 119 is swung upwardly about pivot pin 116 when the magazine cover plate is moved forwardly to uncover the magazine. The rearward end of bell crank lever 119 is pivotally connected at 122 with the rearward end of a double-ended lever 123 which is pivotally connected to plate-supporting lever 113 intermediate the length of the plate-supporting lever by having a transversely-extending intermediate portion thereof pass through an apertured extension 124 provided on lever 113 rearwardly of pivot pin 114. The forward end of lever 123 is pivotally connected to the upper end of a link assembly 125 the lower end of which is pivotally connected to the forward end of lever 115. The link assembly 115 may conveniently comprise a pair of similar, parallel links 125' disposed one at each side of the forward ends of levers 115 and 113. With this arrangement, when the forward end of bell crank lever 119 is swung upwardly by link 58 and the rearward end of this bell crank lever simultaneously swung downwardly carrying with it the rearward end of double-ended lever 123 the extension 124 of plate-supporting lever 113 is moved downwardly and the forward end of plate-supporting lever 115 is simultaneously moved upwardly, resulting in a simultaneous downward movement of the rear ends of both levers 113 and 115 which carries the cartridge elevator plate 47 downwardly and maintains it substantially

11

parallel to the top walls of the magazine chamber at all positions of its downward movement.

The modified mechanism includes the slide 70 having upstanding abutments 72 at the forward end of the magazine chamber and is resiliently urged rearwardly into contact with shoulder 73 by spring 74 surrounding pin 75 which is secured at its forward end to the bottom of a U-shaped bracket 126 mounted on pivot pin 116 and has its rearward end slidably received in an elongated, 10 tubular lug 127 secured to the slide. Slide 70 has upwardly-extending side walls provided with elongated slots 71' which receive the pin 116 and guide the slide in its forward and rearward movements relative to the magazine chamber in the 15 forearm 11. The purpose of the slide is the same as that of the slide 70 in Figures 2 and 7, as described above.

In the modified arrangement shown in Figures 13 and 14, forward movement of the magazine cover plate 44 moves the cartridge elevator plate 47 downwardly to the bottom of the magazine chamber and simultaneously moves the slide 70 forwardly to a small extent so that the contents of a cartridge box can be easily inserted into the magazine chamber. When the cartridges have been inserted and the cover plate is moved forwardly to cover the magazine chamber, the slide 70 is moved forwardly to properly position the cartridges in the magazine chamber and lever 119 is released freeing spring 117 to exert its force in an upward direction on cartridge elevator plate 47 to resiliently urge the cartridges contained in the magazine toward the top of the chamber.

Figures 10, 11 and 12 disclose a modified form of magazine mechanism including a magazine clip or drawer, generally indicated at 130, which is received in the rearward portion of the hollow forearm 11, and is movable downwardly out of the forearm to receive a charge of cartridges therein.

The drawer 130 has a bottom plate 131 which covers the drawer-receiving opening in the bottom wall of the forearm 11 when the drawer is in closed position, as illustrated in Figure 10, and carries a manually-operated latch 132 which releasably secures the drawer in the closed position. A pair of substantially parallel, spaced-apart end walls 133 and 134 extend inwardly from the bottom wall 131 and are connected by a back wall 135 which provides a bottom or rear closure for the drawer. A pair of grooved guides 136 are secured to the rear or left-hand side wall of the forearm and slidably receive extensions of the back plate 135 to guide the drawer or chamber 130 in its movements into and out of the forearm.

The magazine drawer is also guided by a plate 137 depending from the lower forward edge of ramp 138 and contacting the inner face of rear end wall 133 of the magazine drawer.

A movable cartridge elevator plate 139 is positioned within the magazine drawer and guided by an X frame assembly comprising two parallel pairs of cross-over members 140, the two members of each pair being pivotally inter-connected at their mid-length positions. The end wall 131 of the drawer is provided interiorly of the drawer with a pair of spaced-apart, substantially parallel, upstanding ribs 141 each having a pair of spaced-apart, elongated slots therein. The upper end of one of the members 140 is pivotally connected to one of the depending flanges 142 of the elevator plate 139 and is slidably connected with the corresponding rib 141 by having its lower end

12

operatively connected with one of the elongated slots in the rib. The other member of the pair of members 140 is slidably connected with the flange 139 and the rib 141, as is clearly illustrated in Figure 10. With this arrangement the elevator plate 139 may be moved between an elevated position relative to the lower end plate of the magazine drawer, as illustrated in Figure 10, and a position in which it rests upon the inner-surface of end plate 131, as illustrated in Figure 11, the X frame assembly being collapsible to permit such movement of the elevator plate and being extensible when the elevator plate is moved away from the bottom plate 131 to guide the elevator plate and maintain it substantially parallel to the bottom plate at all times.

A lever 143 is pivotally connected at its forward end to the rearward end of plate 139 at the under-surface thereof and extends rearwardly through medial, longitudinal slots provided in plates 133 and 137. This lever is supported at substantially its mid-length position on the upper end of a strut 144 by a pivotal connection 145 between the lever and the upper end of the strut, the strut being pivotally connected at its lower end to the inner-surface of bottom wall 131 immediately to the rear of the lower end of rear end-plate 133 by a pivotal connection 146. The rearward end of lever 143 carries a pin 147 and a loop spring 148 mounted on a suitable bracket, not illustrated, within the rear part of the forearm 11 and bears at its outer end on the pin 147 urging the rearward end of lever 143 downwardly and plate 139 upwardly.

A lever 150, similar to lever 143, is connected at its rearward end to the forward end of plate 139 by a pivotal connection at the under-surface of the plate and is supported intermediate its length by a pivotal connection 151 carried by the upper end of a strut 152, the lower end of which is pivotally connected at 153 to the inner-side of the bottom wall 131 of the magazine drawer immediately in front of the lower end of front end-plate 134 of the drawer, the lever 150 projecting through a longitudinal slot provided in end-plate 134. A loop spring 154 mounted upon a pin 155 and held under tension by a bracket 156 secured in the forearm 11 bears at its rearward end upon a pin 157 carried by the forward end of lever 150 to urge the forward end of this lever downwardly and the forward end of plate 139 upwardly.

When the magazine drawer 130 is pulled out of the forearm of the rifle, as illustrated in Figure 11, the rearward end of lever 143 and the forward end of lever 150 come into contact with the bottom wall of the magazine forearm at the rear and forward ends respectively of the opening provided in the bottom wall for the drawer 130, which contact tilts levers 143 and 150 about pivotal connections 145 and 151 forcing cartridge elevator plate 139 downwardly against the inner-face of the bottom wall 131 of the magazine drawer, as illustrated in Figure 11. With the elevator plate 139 in the position illustrated in Figure 11, the contents of a conventional cartridge box may be inserted into the magazine drawer 130 on top of the plate 139. The drawer is then forced back into the magazine and locked in position by latch 132 whereupon springs 148 and 154 are rendered effective to resiliently urge the elevator plate 139 upwardly holding the cartridges against the movable top wall 49 of the magazine. Magazine drawer 130 is provided with 75 a slidable top plate 158 which closes the upper

end of the drawer when the drawer is in the projected position, illustrated in Figure 11, to prevent cartridges inserted in the drawer from being pushed out of the top end of the drawer and over the upper ends of the drawer end-walls 133 and 134. This slidable top plate 158 extends beyond the upper end of front end-wall 134 and is provided in its extending end portion with a hole or aperture 159 which receives a pin 160 projecting downwardly from the movable top wall 49. When the drawer is moved back into the magazine to the position illustrated in Figure 10, pin 160 enters the aperture in slidable top wall 158 of the magazine drawer and locks this slidable top plate 158 with the movable top wall 49 of the magazine so that both plate 158 and wall 49 are withdrawn when the plunger 84 is moved forwardly to admit a row of cartridges into the feed chamber between wall 49 and top fixed wall 80 of the magazine.

In this arrangement the cartridge feed mechanism, including plunger 84, pusher 92, bolt 13, and the remainder of the breech mechanism, not illustrated in detail, may be the same as that described above in connection with Figures 1 to 9 inclusive, and a detailed description thereof is not believed to be necessary for a complete understanding of the modified magazine mechanism illustrated in Figures 10, 11 and 12.

Figures 15, 16 and 17 illustrate a modified form of breech bolt and firing mechanism which may be operatively associated with any of the magazine mechanisms herein described.

The receiver, generally indicated at 162, comprises a hollow, rectangular body having a top wall 163, an end wall 164, and side wall 165 extending downwardly from the top wall 163, the bottom and front of the hollow receiver preferably being left open for cooperation of the stock and magazine therewith. A pair of upper side walls 166 and 167 extends upwardly from the top wall 163 along the opposite edge thereof and are provided at the upper edges of their forward portions with opposed groove sections 168 and at their rear ends with short groove sections 169 which groove sections provide a guideway extending longitudinally of the receiver for the breech bolt, generally indicated at 170.

The breech bolt comprises an elongated, tubular member 171 slidably received between the side walls 166 and 167 extending upwardly from the top wall 163 of the receiver and provided with diametrically-opposed laterally-extending wing sections 172 and 173 slidable in the groove sections 168 and 169 of the receiver to guide the bolt for longitudinal movement in the receiver.

The front wing sections 172 extend for a short distance lengthwise of the breech bolt and are slidably received in the long groove sections 168 at the forward end of the receiver, while the rear wing sections 173 on the breech bolt extend longitudinally of the bolt substantially one-half of the bolt length and are slidably received in the short groove sections 169 at the rear end of the receiver. A cylindrical lug 174 is secured on one side of the tubular member 171 adjacent the mid-length position thereof and rotatably receives the perpendicular-extending end portion of a breech bolt lever 175. The lever 175 moves up and down independently of the breech bolt to engage it with or release it from an abutment shoulder 176 provided on the side wall 167 at the forward end of the corresponding rear groove section 173. When the lever 175 is engaged in front of the shoulder 176, as illustrated in Figure

16, the bolt is locked in firing position. The lever may be raised to release it from the shoulder and the bolt then retracted rearwardly of the receiver to eject an empty shell from the chamber of the barrel 10 and inject a new shell into the barrel chamber.

A hammer rod, generally indicated at 177, extends longitudinally through the tubular member 171 of the breech bolt and is provided at its forward end with a cylindrical hammer 178 which has a sliding fit with the interior of the tubular member 171. A reduced portion 179 of the hammer rod extends rearwardly from the hammer to an annular shoulder 180 and from this shoulder the rearwardly-extending portion of the rod has a diameter such that it slidably fits the interior of the tubular member 171. A coiled firing spring 181 surrounds the reduced portion 179 of the hammer rod between the hammer and an abutment pin 182 which extends transversely through the tubular member 171.

A pivot pin 183 is mounted in the rearward portion of the hollow receiver by apertured brackets 184 secured to the interior of the receiver and receiving the ends of pin 183, pin 183 extending longitudinally of the interior of the hollow receiver forwardly from the rear wall 164 a distance sufficient to support a sear, generally indicated at 185, thereon.

Sear 185 comprises a generally rectangular bottom portion 186 extending along pin 183 and having secured to its side adjacent the pin a bearing sleeve 187 through which the pin extends to pivotally mount the sear on the pin. An arm 188 projects upwardly from the upper end of the rectangular bottom portion 186 of the sear to a position substantially diametrically opposite the center-line of the breech bolt 170 and is there provided with a perpendicularly-extending detent 189 which extends through an elongated slot 190 in the tubular member 171 for engagement with the annular shoulder 180 of the hammer rod 177.

When the breech bolt is drawn rearwardly to its limiting position, shoulder 183 is positioned to the rear of detent 189, and when the breech bolt is subsequently moved forwardly, hammer rod 177 is held against forward movement by engagement of detent 189 with shoulder 180, thereby compressing the firing spring 181 and cocking the rifle for firing by the trigger 191.

Trigger 191 is pivotally mounted on a pivot pin 192 which extends transversely through the hollow breech block and is secured at its ends in the downwardly-extending side walls thereof and has a rearwardly-extending arm 193 which engages at its rear end in an apertured lug 194 extending from the front edge of the rectangular bottom portion 186 of the sear under the pivot pin 183, so that movement of the trigger is effective to rock the sear about the pin 183 to release the detent from its engagement with the shoulder 180 to fire the rifle.

A loop spring 195 is coiled about the trigger pin 192 and bears at one end against the rearward side of trigger 191 and at its opposite end against the under-side of forward sear pin supporting bracket 184. This spring resiliently urges the trigger forwardly and at the same time urges the upper end of the sear inwardly so that the sear detent automatically engages the shoulder 180 when the bolt is retracted.

A transverse guide block 196 rests upon the upper surface of receiver top wall 163 between the upwardly-extending side walls of the receiver and is positioned near the rearward edge of feed slot

81 when the breech bolt is in the closed position, illustrated in Figure 15. A guide rod 197 extends rearwardly from the guide block 196 and near its rearward end passes through an apertured lug 198 secured to and extending upwardly from the top wall 163 of the receiver. The rearward end of the guide pin is extended upwardly perpendicular to the remainder of the pin to provide a detent 199 extending into an elongated slot 200 provided in the bottom portion of the tubular member 171 adjacent the rearward end thereof. A coiled compression spring 201 surrounds the guide pin 197 between the guide block 196 and the apertured lug 198.

A bifurcated cartridge injector 202 is slidably supported on the top wall of the breech block and is secured at its rearward end against the forward face of guide block 196. A firing pin 203, preferably of inverted U-shaped cross-section extends downwardly from the hammer 178 between the oppositely-disposed legs of the bifurcated injector 202 and is provided at its upper forward corner with a firing point 204 for discharging the rim-fire cartridges. This firing pin extends upwardly from the top surface of the upper wall 163 of the receiver to the hammer 178 and has its upper edge portion slidably received in an anvil 205 secured in the forward end of tubular member 171 closing the same except for the upper portion of movable firing pin 203.

An extractor 206 is secured to the upper-side of the front end of the tubular member 171, above the firing pin, to engage behind the head of a cartridge 207, as illustrated in Figure 15, to withdraw the cartridge from the chamber in the barrel 10.

In the operation of this modified form of breech bolt and trigger mechanism, when the bolt is retracted the shoulder 180 of the hammer rod is moved rearwardly of the detent 189 on sear 185 and at the same time the flat injector 202 is moved rearwardly of the feed slot 81 in the top wall of the breech block. A cartridge is then forced upwardly through the feed slot to a position immediately above the top wall of the breech block and is held in this position by the rearward end portions of cartridge guides 102 which are provided in this form of the invention in the same manner as illustrated in Figures 4, 8 and 9 and described above.

When the breech bolt 170 is now moved forwardly from its retracted position the sear detent 189 engages shoulder 180 and holds hammer rod 179 retracted. Injector 202, however, is moved forwardly by spring 201 and enters the cartridge into the converging end portions of the semi-cylindrical guides 102 toward the ramp 103. When the cartridge has been properly turned in the guides 102 it is picked up by the anvil 205 and forced up the ramp 103 and into firing position in the barrel chamber, as illustrated in Figure 15, firing pin 203 being held retracted by the trigger sear and injector 202 being stopped by the converging guides shortly after the cartridge has been turned in the guides to present its bullet end to the rearward opening of the barrel chamber. As soon as the bolt has been moved to its forward limiting position, lever 175 is turned downwardly to engage in front of shoulder 176 on the receiver and at the same time extractor hook 206 will be engaged ahead of the base rim on the cartridge, as is also clearly illustrated in Figure 15. Pulling the trigger will now release the hammer rod 177 and spring 181 will drive the hammer forwardly with the firing pin 203 until

the point 204 of the firing pin strikes the rim of the cartridge and the firing pin is in the forward position, illustrated in Figure 15. If now, the lever 175 is raised to free it from shoulder 176 and bolt 170 retracted, the firing pin 203 will be held in its forward position by the force of spring 201, while the bolt is drawn rearwardly carrying with it the extractor 206. As the cartridge is withdrawn from the barrel, the firing pin will continue to exert a forwardly-directed resilient force on the bottom edge of the cartridge shell, until the forward end of the empty shell is just clear of the rear end of the barrel at which time this force will flip the cartridge upwardly out of the barrel and clear of the mechanism. The forward movement of the firing pin is limited by contact of the front end of hammer 178 with anvil 205. As retraction of the bolt is continued, front end of slot 200 will contact detent 189 on guide pin 197 to pull the injector 202 back past the feed slot 81 whereupon a new cartridge will be injected into the receiver and may be loaded in the manner described above upon forward movement of the breech bolt.

The above-described arrangement, as illustrated in Figures 15, 16 and 17, provides a simplified breech bolt and trigger mechanism, particularly adapted for use with a magazine which supplies cartridges to the breech mechanism in a position transverse to the longitudinal axis of the breech mechanism and barrel.

Figures 18 to 21 inclusive illustrate a simplified form of magazine mechanism in which the cartridges are arranged in a single row and extend transversely of the longitudinal axis of the rifle barrel and breech mechanism, but are inserted into the magazine singly rather than being dumped from a cartridge box into the magazine in a single operation.

In the magazine arrangement illustrated in Figures 18 to 21 inclusive, the firearm is provided with a forearm 210 which may be of generally conventional construction and may, if desired, be formed of a suitable material such as plastic or wood. This forearm 210 is recessed in the face thereof adjacent the barrel 10 to provide a well or opening 211 extending from the front end of the forearm to the receiver of the rifle. This opening 211 receives an elongated magazine, generally indicated at 212, comprising a tubular casing having a length substantially equal to the length of the forearm and a rectangular cross-sectional shape of a thickness substantially equal internally, to the base diameter of a cartridge plus the thickness of the strip 214, and a width having an internal dimension substantially equal to the length of a cartridge so that a single row of cartridges 213 can be disposed in this magazine with the cartridges extending transversely of the magazine casing. In the arrangement illustrated, the bottom wall of the magazine casing 214 is longitudinally slotted and this slot is covered by a slidable strip 215 extending longitudinally through the casing at the bottom thereof. A strap 216 is secured to the forward end portion of the strip 215 and extends forwardly of the casing and is provided on the upper surface of its forward end with a cylindrical lug 217 and at its lower surface with a flat hook 218 carrying a pivoted latch 219 for a purpose which will presently appear. A guide tube 220 is secured at its rearward end to the forward end of the casing 214 and extends forwardly through the lug 217. A coiled compression spring 221 surrounds the guide tube 220 between

the forward end of the casing and the lug.

With this arrangement, the strip 215 is urged forwardly of the casing 214 by the force of spring 221 and may be moved rearwardly by manual force applied to the outer end of hook 218. Movement of strip 215 forwardly and rearwardly of the casing is limited by suitable stop means which may comprise a bar 222 secured at its ends to the casing and extending transversely across the strip 215, a stop 223 secured to the strip at the rearward side of bar 222 and the rearward end of strap 216.

A rear abutment 224 is positioned within the rearward end of casing 214 and secured to the rear end of strip 215 which abutment has a sliding fit in the rear end portion of the casing and is urged forwardly by spring 221 to a position in which it covers cartridge feed slot 225 in the rear end portion of the top wall of the casing 214. This abutment has a limiting rearward position in which its forward edge is just to the rear of the feed slot 225, as is clearly illustrated in Figure 18.

A pair of inclined ramps 226 are secured in the rearward end portion of the casing leading from the bottom wall of the casing forwardly and upwardly to the rear edge of feed slot 225 at each end thereof and abutment member 224 is transversely dimensioned to pass between these ramps.

A detent 227 is provided at the front end of forearm 210 which detent is engageable by latch 219. When the magazine is inserted into the opening 211 in the forearm the rear end of the casing first comes into contact with the wall at the rear end of recess 211, after which lug 217 and hook 218 are forced inwardly compressing spring 221 until latch 219 engages detent 227 in which position of the parts abutment 224 has its forward edge positioned slightly to the rear of the rear edge of feed slot 225, as shown in Figure 18, and the cartridges 213 may then pass from the interior of the casing up the ramps 226 and through the feed slot into the breech mechanism of the rifle.

When latch 219 is released from detent 227 and the magazine withdrawn from the forearm, spring 221 expands moving abutment 224 forwardly until it is positioned somewhat ahead of feed slot 225, as clearly illustrated in Figure 19.

A pair of openings 238 are provided one in each side wall of the magazine casing 14 in the rearward end thereof and in position such that they expose the forward portions of the ends of the abutment 224 when in the forward position, illustrated in Figure 19. A pusher 228 is slidable in the interior of the casing and is connected at its forward side to the rear end of a stem 229 which extends forwardly through the casing and into the guide tube 220 which extends forwardly from the front end of the casing. A coiled compression spring 230 surrounds stem 229 between the pusher 228 and the rearward end of guide tube 220 to resiliently urge the pusher rearwardly in the casing.

A flap 231 is pivotally secured at its rearward edge to the rearward end of the magazine casing 214 and extends forwardly beneath the casing to the side wall openings 227 where it is provided with a pair of upstanding ears 232 which cover the openings when the flap is closed against the underside of the casing. When the casing is removed from the forearm of the rifle this flap is swung downwardly to uncover the side openings 227 and a cartridge may then be inserted, bullet

end first, into the magazine through one of the side wall openings. The ends of abutment 224 are recessed, as indicated at 233, so that the bullet end of a cartridge can be started between the front edge of the corresponding end of the abutment and the rearward edge of the corresponding end of pusher 228 to wedge the pusher away from the abutment and permit the bullet to be forced between the abutment and the pusher.

10 In inserting the cartridges into the magazine it is preferred to insert a cartridge bullet-end first through one of the openings 227 and then to insert a second cartridge bullet-end first through the opposite opening 227, as illustrated in Figure 19, so that the cartridges will be arranged in opposite end-to-end relationship in the casing of the magazine.

15 As the cartridges are forced into the magazine through the openings 227 the pusher 228 is moved forwardly, compressing spring 230, until the magazine is filled.

20 After the magazine has been filled, as indicated above, it is re-inserted in the opening 211 in the rifle forearm and the hook 218 forced rearwardly until latch 219 engages detent 227. This positions abutment 224 at the rearward edge of feed slot 225 so that cartridges will be fed from the magazine into the breech mechanism of the rifle, as indicated above.

25 30 This magazine mechanism may be used in combination with either of the breech bolt and trigger mechanisms hereinabove described as may any of the other magazine mechanisms previously described herein.

35 40 The above-described devices provide a simplified gun construction, in which a large number of cartridges may be stored in the magazine by arranging the cartridges transversely of the longitudinal center-line of the rifle barrel and breech mechanism. In some of the modifications above-described, an entire box of cartridges may be inserted into the rifle magazine in a single operation and may be subsequently divided into groups of a number less than the entire contents of the box

45 for string firing or other purposes. There is herein-described suitable magazine mechanism for holding the cartridges in the transverse position indicated and for feeding such cartridges one-by-one into the breech mechanism of the rifle

50 55 and suitable breech-bolt and receiver mechanism effective to orientate the cartridges so that the bullet end is always presented to the barrel chamber as the cartridges are inserted into the barrel, for inserting the cartridges, ejecting the empty shells from the barrel and rapidly firing the cartridges, if desired, by operation of the improved breech-bolt mechanism.

60 While a manually operated, multiple shot rifle has been shown for the purpose of illustrating the invention, the magazine mechanisms are applicable to a fully automatic rifle, if such a combination should be desired.

65 The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

70 75 What is claimed is:

1. A cartridge feeding magazine insertable into an elongated, magazine receiving recess dis-

posed between a rifle barrel and forearm and communicating with a receiver at the breech end of the rifle barrel, said magazine comprising an elongated tubular casing of substantially rectangular cross sectional shape having an internal thickness somewhat greater than the diametrical thickness of a cartridge and an internal width substantially equal to the length of a cartridge, said casing having a longitudinally-extending slot in the bottom wall thereof and a transverse, cartridge feed slot in the rearward portion of its upper wall, a tubular guide secured to said casing and extending forwardly from the forward end of the latter, a strip slidably disposed longitudinally of said casing against the bottom wall thereof, an abutment within the rear portion of said casing secured to the rear end of said strip, an apertured lug secured to the front end of said strip slidably receiving said tubular guide, a flat hook secured to the forward end of said strip, a latch carried by said hook and engageable with a detent in the forward end of the rifle forearm to releasably secure said magazine in operative position in the magazine receiving recess, a cartridge pusher slidably in said casing and having a stem slidably received in said tubular guide, a compression spring surrounding said stem between said pusher and said tubular guide urging said pusher rearwardly of said casing, said casing having a pair of cartridge-receiving openings disposed respectively in the side walls near the rear end of said casing, and a compression spring surrounding said tubular guide between the forward end of said casing and said guide receiving lug for moving said abutment forwardly to close said feed slot when said magazine is removed from the rifle.

2. A cartridge feeding magazine insertable into an elongated, magazine receiving recess disposed between a rifle barrel and forearm and communicating with the receiver at the breech end of the rifle, said magazine comprising an elongated tubular casing of rectangular cross sectional shape dimensioned to slidably receive cartridges disposed transversely thereof, said casing having a cartridge feed slot extending transversely of its upper wall near the rear end of the latter, a tubular guide secured to the front end of said casing and extending forwardly therefrom, a strip extending longitudinally through said casing adjacent the bottom wall of the latter, a lug on the front end of said strip slidably receiving said tubular guide, an abutment on the rear end of said strip slidable in said casing at the rear end of the latter, resilient means interposed between said casing and said lug urging said abutment to a position in which it covers said feed slot, a cartridge pusher slidable in said casing and having a stem slidably received in said tubular guide, and resilient means between said pusher and said tubular guide urging said pusher rearwardly of said casing, said casing having respective cartridge-receiving openings in its side walls adjacent said feed slot and said abutment having recesses in its front corners to facilitate insertion of cartridges into said casing.

3. A cartridge feeding magazine insertable into an elongated, magazine receiving recess disposed between a rifle barrel and forearm and communicating with the receiver at the breech end of the rifle barrel, said magazine comprising an elongated tubular casing of rectangular cross sectional shape dimensioned to slidably receive cartridges disposed transversely thereof, said casing having a cartridge feed slot extending transversely of its upper wall near the rearward end of the latter, a tubular guide secured to the front end of said casing and extending forwardly therefrom, a strip extending longitudinally through said casing adjacent the bottom wall of the latter, a lug on the front end of said strip slidably receiving said tubular guide, an abutment on the rear end of said strip slidable in said casing at the rear end of the latter, resilient means interposed between said casing and said lug urging said abutment to a position in which it covers said feed slot, a cartridge pusher slidable in said casing and having a stem slidably received in said tubular guide, resilient means between said pusher and said tubular guide urging said pusher rearwardly of said casing, said casing having respective cartridge-receiving openings in its side walls adjacent said feed slot, and means carried by said strip and engageable with a forearm carried detent for holding said abutment rearwardly of said cartridge feed slot when said magazine is operatively assembled with a rifle.

4. A cartridge feeding magazine insertable into an elongated, magazine receiving recess disposed between a rifle barrel and forearm and communicating with a receiver at the breech end of the barrel, said magazine comprising an elongated tubular casing slidably receivable in said recess and of substantially rectangular cross sectional shape dimensioned to slidably receive a string of cartridges disposed transversely thereof, said casing having a cartridge feed slot in its top wall and respective cartridge injecting openings in its side walls near the rear end of said casing, an abutment slidable in said casing near the rear end of the latter, spring means urging said abutment to feed slot closing position, means acting against said spring means to hold said abutment in feed slot opening position when said magazine is assembled with a rifle, a cartridge pusher in said casing and spring means urging said pusher rearwardly of said casing.
